Attorney.

UNITED STATES PATENT OFFICE.

THOMAS ROBERTS, OF BALTIMORE, MARYLAND.

MOTOR FOR STREET-CARS.

SPECIFICATION forming part of Letters Patent No. 445,756, dated February 3, 1891.

Application filed February 15, 1890. Serial No. 340,564. (No model.)

To all whom it may concern.

Be it known that I, THOMAS ROBERTS, a citizen of the United States, residing at Baltimore, in the State of Maryland, have invented 5 certain new and useful Improvements in Motors for Street-Cars, &c.; and I do declare the following to be a full, clear, and exact description of the invention, such as will enable others skilled in the art to which it appertains 10 to make and use the same, reference being had to the accompanying drawings, and to the letters of reference marked thereon, which form a part of this specification.

My invention relates to improvements in 15 that class of locomotives that are noiseless and smokeless, so as to be better adapted for street traffic than those now in use; and the object of my invention is to produce a locomotive, dummy, traction, or portable engine 20 that is noiseless, as the exhaust-steam is entirely condensed, and can be used over and over again for feeding the boiler with water. It is smokeless, as only coke is used as fuel instead of coal; also, to occupy a very small 25 space for the boiler, engines, condensers, and operating machinery, and, finally, to greatly reduce the expenses of building and running the locomotive, &c., and with greater safety to pedestrians and animals than has been the 30 case heretofore.

With these objects in view my invention consists in the construction of certain details and arrangement of parts, as will be more fully described hereinafter, and specifically 35 pointed out in the claims, reference being had to the accompanying drawings and the letters of reference marked thereon.

Like letters indicate similar parts in the different figures of the drawings, in which— 40 Figure 1 represents a longitudinal section of a street-locomotive having my improvements attached. Fig. 2 is a vertical cross-section of Fig. 1 on line *xx*.

In the accompanying drawings, A represents a suitable body or cab of a dummy or street locomotive or motor as used on ordinary tramways or street-railroads, and in said body my improvements are arranged in the manner hereinafter more specifically described. These improvements consist of a 45 vertical tubular boiler B, preferably placed

near one end of the motor and having a suitable grate for burning coke, which, as is well known, produces no perceptible smoke. Said boiler is covered with a non-conducting material or casing to prevent radiation of heat. 55 At the opposite end of the motor are arranged the engines E, which are preferably of the oscillating compound type. They are connected directly to the cranks of one of the 60 axles, which is in turn connected by the usual side rod F with the other axle. The cranks are placed at an angle of ninety degrees, and the high-pressure cylinder is connected to one crank and the low-pressure cylinder to the 65 other crank. The steam generated in the boiler passes through the steam-pipes (shown in dotted lines in Figs. 1 and 2) and through the hollow trunnions into the high-pressure cylinder *a*, and after exerting its pressure on 70 its piston it passes through the hollow intermediate trunnion connecting the two cylinders into the low-pressure cylinder *b*, and after expending its force on the piston in said cylinder it passes to the condensers C by 75 means of the exhaust-pipe *u*. If desired, a part of the exhaust-steam may be led into the smoke-stack, forming a steam-jet to assist in creating a draft by a branch pipe *v*. The trunnions are provided with suitable openings and partitions or diaphragms to properly 80 admit and exhaust the steam as required. The condensers C, preferably one on each side, are formed of a rectangular casing provided with tubes *e*, extending fore and aft 85 through the casing for the passage of air. Between said tubes *e* are arranged the diaphragms *f*, by which a zigzag course is imparted to the steam. Any uncondensed steam in the condenser passes through the perforation *g* into the hollow roof G, which is made of galvanized iron or other suitable material. 90 A non-conducting covering may be placed over said roof to prevent radiation of any heat. The roof is provided with an oblong central opening *h* for the passage of air, and, if necessary, on each side with additional openings *i* to obtain a very large cooling or condensing surface. At each end of the openings are placed dampers or valves *k* for regulating the amount of air passing through said 95 openings. In one or both ends of the con-

densers C doors may be arranged to gain access to their interiors for repairs, inspection, &c. The water of condensation in the condensers passes through the pipes c into the 5 tanks D, placed under the floor of the motor, and any condense-water in the hollow roof descends through the conduits m, placed in the corners of the cab, and thence into said tanks which form the feed-tanks. If desired, 10 the tank may, however, be divided, and one be placed at each end of the cab instead of being placed in the middle.

In some instances a horizontal boiler may be preferred instead of the vertical one, and 15 in this case the engines may be attached to the boiler by suitable brackets or secured to the floor, as desired. In other cases it may be desirable to have the motive power—i. e., the boiler and engines—contained in the same 20 structure with the seats for the passengers instead of having a separate cab for containing the same. In this case the boiler and engines are placed in a small separate compartment, divided by a partition, and arranged at one end of the car. The engines 25 may then also be attached by suitable brackets to the boiler, if desired, so as to occupy less space. This arrangement can be readily planned by any skilled engineer, and I have 30 therefore not illustrated the same by the usual drawings. In ascending heavy grades the live steam from the boiler may be also admitted into the low-pressure cylinder, if desired, by which greater power can be exerted.

35 The condensers may be made of any suit-

able material and of any size desired to obtain the proper amount of cooling-surface, and they may be placed wherever desired to obtain a free passage of air through them. 40

Having thus described my invention, what I claim, and desire to secure by Letters Patent, is—

1. In motors, the condensers C, provided with tubes and diaphragms, as described, and 45 placed on each side of the cab, in combination with the engines, as specified.

2. In motors, the condensers C, provided with tubes and diaphragms, as described, and placed on each side of the cab, in combination 50 with the hollow roof provided with an oblong central opening h and openings i and connected to a feed-tank, substantially as shown and set forth.

3. In motors, the hollow roof provided with 55 an oblong central opening having dampers k, in combination with the condensers C, provided with tubes and diaphragms and connected to feed-tanks placed under the floor, all arranged as and for the purpose specified. 60

4. In motors, the hollow roof provided with central and side openings having dampers, and the condensers C, arranged as shown, in combination with a feed-tank and a pair of oscillating compound engines, all as set forth. 65

In testimony whereof I affix my signature in presence of two witnesses.

THOMAS ROBERTS.
